CLAIM

The ornamental design for a solid-state disk as shown and described.

DESCRIPTION

FIG. 1 is a bottom, front, and left side perspective view of a solid-state disk showing our new design;

FIG. 2 is a top, rear, and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the solid-state disk that form no part of the claimed design.

1 Claim, 8 Drawing Sheets
